Application September 29, 1949, Serial No. 118,608

10 Claims. (Cl. 101—282)

1

This invention relates to printing presses, particularly to the printing couple of a press of the flat bed type in which the reciprocatory bed and the impression cylinder are connected together by gearing for simultaneous operation, and the cylinder is driven by power taken from the bed.

Those familiar with the construction and operation of printing presses of this general type appreciate the need to maintain the peripheral speed of the surface of the impression cylinder the same as the linear speed of advancement of the bed when the bed is moving upon its printing stroke. Any relative movement between bed and cylinder during a printing operation, of course, results in the blurring of a transversely extending elongated area of the printed sheet and hence in a defective printing operation. Furthermore, if the construction is such that any such relative movement between members of the couple occur regularly at a predetermined point in the travel of the bed the printing surface will be worn due to repeated slippage between the cylinder and a definite although rather small area of the printing form. It is, of course, highly important to minimize the possibility of the production of defective printed matter and wear of the printing surface and it is the principal object of the present invention to provide a means for positively preventing slippage or relative movement of the members of the printing couple of a printing press during a printing operation.

A means commonly employed to effect oscillation of the impression cylinder of a flat bed press in synchronism with the movements of the bed comprises a rack rigidly mounted upon the bed and disposed in parallelism to the axis of bed movement and a circular gear rigidly mounted upon the cylinder, the teeth of rack and gear intermeshing as closely as may be so as to minimize backlash and relative movement between the members to which the toothed elements are respectively secured. Backlash may be present when the teeth of rack and gear intermesh imperfectly due to defects in original design or construction, or may result from wear. The usual automatic bed and cylinder press is designed to print several thousand sheets per hour and hence wear in the gearing connecting bed and cylinder will inevitably occur.

The bed of such a press is, of course, driven with an accelerating-decelerating motion regardless of the specific nature of the driving means employed. Thus the bed will start on its printing stroke from a position of rest and will be

accelerated to approximately the midpoint of its travel after which it must of necessity be gradually decelerated in order to bring it smoothly to a stop at the end of its printing stroke. The driving means employed may cause the bed to move with simple harmonic motion in its acceleration-deceleration cycle, or may impart specifically different acceleration-deceleration movements. In any event, however, the cylinder, as well as the bed, will first be accelerated, and will then be decelerated, during the printing operation, the movements of the cylinder following the movements of the bed.

The cylinder with its associated gearing comprises a structure of considerable mass and, after it has been accelerated to maximum speed will tend to continue to rotate at that speed due to its momentum or flywheel action, the force due to momentum being great enough to overcome the frictional resistance due to pressure of the cylinder against the bed bearers and form. At some point in the travel of the bed following that at which deceleration commences the rearward face of the cylinder gear tooth which is then engaged by the forwardly directed face of the rack tooth which is pushing it will separate itself from such rack tooth surface, if there is any play or backlash in the gearing, and the forward and heretofore inactive face of that cylinder gear tooth will advance and contact the rearwardly facing or trailing face of the preceding rack tooth, the cylinder gear momentarily advancing faster than the bed rack by reason of the aforesaid flywheel action of the cylinder and the slowing down of the bed. It is at this point, and by reason of this slight relative movement of the cylinder gear and the bed rack, that the slurring of the printed sheet and wear of the printing surface occurs.

In accordance with the present invention there is associated with one member of the printing couple, preferably the bed, means for positively acting upon the second member of the printing couple in such manner as to prevent the trailing face of the then active tooth of the driven member from leaving the forward face of the then active tooth of the driving member when deceleration of the driving member on its printing stroke first begins. The invention may have a number of different embodiment but in the case of the flat bed press in which the bed is positively driven and the cylinder is oscillated by power transmitted to it directly from the bed, there is included an inertia device which is constrained to bodily move with the bed at all times

3

but which is so supported that it may move forwardly in the direction of the printing stroke relatively to the bed when deceleration of the bed first begins to take place.

This weight or inertia device is connected, by means of suitable motion multiplying levers, to a rack which is mounted upon the bed for sliding movement in a direction parallel to the direction of the bed motion. Forward movement of the weight results in slight rearward movement of the rack, relatively to the bed, and the teeth of this sliding rack are in constant mesh, in all positions of adjustment, with the teeth of a secondary gear or gear segment rigidly mounted upon the cylinder. Hence a force is transmitted by the sliding rack to the cylinder tending to rotate the cylinder in a direction opposite to that in which the cylinder is already rotating about its axis and the application of this force causes the rearwardly facing surface of the then active tooth of the cylinder main gear to maintain close contact with the forwardly facing surface of the then active tooth of the main rack so that separation of these surfaces and relative movement of bed and cylinder is prevented. As the forward movement of the inertia device associated with the bed is caused initially by deceleration of the bed, continued deceleration of the bed will have the effect of maintaining the inertia device active in its application of force to the sliding rack so that relative movement of cylinder and bed due to backlash or play in the connecting gearing is prevented during the entire period of bed deceleration, or until the printing stroke has been completed. When the motion of the bed is reversed and it decelerates during the final period of its non-printing stroke the inertia device will, of course, move in the opposite direction relatively to the bed and pressure of the teeth of the sliding rack against the mating teeth of the cylinder gear or gear segment will be relieved. The printing couple, however, upon the return stroke or movement of the bed performs no printing operation and hence no special means to eliminate backlash need be provided although such could be readily added if considered necessary or desirable. The mechanism described is fully effective when it is needed, i. e. during the entire movement of deceleration of the bed when moving upon its printing stroke.

As previously stated, the invention may be embodied in printing presses which vary in detail and, without departure from the invention, the arrangement and design of its component elements may be considerably modified. One form thereof is illustrated in the accompanying drawings by way of example.

In the drawings:

Figure 1 shows in side elevation, in dotted lines, the frame and certain of the movable parts of a flat bed press, the bed, cylinder, bed oscillating means and the automatically operating mechanism for eliminating play or backlash upon the printing stroke of the bed all being shown in full lines;

Figure 2 is a view of the bed of the press as seen from below, the inertia device being illustrated;

Figure 3 is a section on line 3—3 of Figure 2;

Figures 4 and 5 are in the nature of mechanical diagrams, Figure 4 showing in perspective a portion of the bed, a member representing the cylinder, and the driving connection between bed and cylinder, the sliding rack mounted on the bed being illustrated in the position which is oc-

4

cupies when the bed is in its acceleration phase while on its printing stroke and when moving upon the latter portion of its return stroke, and Figure 5 being a similar view, showing the relative positions of the sliding rack on the bed and the intermeshing gear segment on the cylinder when the bed is decelerating toward the latter part of its printing stroke.

The frame 10 of the press and many of its operating elements, including the sheet feeding means and sheet delivery means, are either illustrated in dotted lines or are omitted and it will be understood that any suitable frame or sheet handling mechanism may be employed. 15 The bed of the press is generally indicated at 12 and this likewise may be widely varied in its details of construction. It is supported for movement in a horizontal plane and the means for effecting its reciprocation or oscillation in this 20 plane is, in part, illustrated in Figure 1.

The shaft 13, extending horizontally and transversely of the press, has fixed upon it at one end a gear 14 adapted to be driven by power from any suitable source. A lever 15 is pivotally supported at 16 for rocking movement about an axis parallel to the axis of shaft 13. Gear 14 and lever 15 are interconnected by means of a link 17, link 17 being pivotally connected to gear 14 at 18 and to lever 15 at 19. The upper end of lever 25 15 is connected by means of a link 20 to the bed 12. As the gear 14 rotates the bed will be advanced from the position in which it is shown in full lines in Figure 1 to the position in which it is indicated in dotted lines in this figure, passing 30 under the impression cylinder 22 in such movement and cooperating with the cylinder in the printing of a sheet which is then superposed upon the cylindrical surface of the impression cylinder. From its dotted line position (Figure 35 1), the bed is moved on its return stroke by the mechanism described until it again reaches the position in which it is shown in full lines. This forward and return movement of the bed is rapidly repeated during the press operation, each 40 successive printed sheet being withdrawn from the cylinder after a printing operation has been performed and delivered onto a pile by delivery mechanism generally indicated at D, and a fresh sheet seized by the cylinder grippers. Upon its 45 printing stroke the cylinder rests directly on the bed, the narrow cylindrical cylinder bearing surfaces 24 and 25 at opposite ends of the cylinder 50 22 making rolling contact with the flat horizontal upward surfaces of the two elongated bearer members 26 and 27 mounted upon the bed. This arrangement is also of conventional character.

The means for imparting to the cylinder the oscillatory movement of the bed comprises an elongated rack 28 rigidly secured to the bed and extending parallel to its direction of movement, the teeth of this rack being in constant mesh with the teeth of a cylindrical gear 30 rigidly secured to the cylinder at one end thereof. As the bed reciprocates rotation of the cylinder about its axis 60 is thus effected and, on the printing stroke of the bed, a sheet secured upon the surface of cylinder 22 will be brought into rolling contact with the upwardly facing surface of the type or printing member affixed to the bed.

In order to prevent slippage of the cylinder relatively to the bed, slurring of the sheet, and wear of the printing surface at the instant when slippage of the cylinder relatively to the bed would 65 normally take place, I provide a relatively simple 70 75

mechanism. This includes a gear segment 32 which may be rigidly secured to that end of the cylinder remote from gear 30 by means such as bolts 33 which pass through slots 32a in the segment, so that the angular position of the segment upon the cylinder may be adjusted when necessary. This mechanism also includes a rack 34 mounted upon that side of the bed 12 which is remote from rack 28, and so secured to the bed that it may be moved relatively to the bed, to a limited extent, in a direction parallel to the bed motion. Thus it is attached to the bed by machine screws 35 which extend through slots 34a formed in the body of the rack. The upwardly extending teeth of the sliding rack 34 mesh with the teeth of the gear segment 32 of the cylinder during the final portion of the printing stroke of the bed but do not intermesh while the bed is being accelerated. The inertia device or weight previously referred to is indicated at 38 and is seen to comprise a member adjustably mounted upon a lever 39 which is pivotally connected at 40 to the bed, lever 39 extending transversely of the bed so that it may rock in a fore and aft direction to a limited extent. Forward movement of the lever 39 is terminated by contact of member 38 with a transverse web portion 12a of the bed, a leaf spring or other cushioning device 41 being provided to absorb any possible shock of impact between member 38 and member 12a. Motion of lever 39 in the opposite direction is limited by means of stop 42 and the free end of this lever is adapted to be supported by a horizontally extending member 12b which is integral with or rigidly attached to the undersurface of bed 12. A helical tension spring 43 normally tends to maintain the lever and weight in the position in which these elements are illustrated in full lines in Figure 2. The direction of the printing stroke of the bed shown in Figure 2 is indicated by the arrow P.

During the first half of the return stroke of the bed the lever 39 will occupy the position in which it is shown in dotted lines in Figure 2 but, during the deceleration period at the termination of the return stroke, the weight and lever will move to full line position, in which position it will remain until the printing stroke has been largely completed and bed deceleration has begun.

Movements of lever 39 are communicated to the sliding rack 34 by means of an intermediate lever 50 the end of the longer arm of which is connected by a link 51 to lever 39 at a point close to the pivot 40, lever 50 being mounted for rocking movement about a pivot 52. A short extension, or arm, 53 of lever 50 projects into a slot or recess formed in the inner face of the sliding rack 34 and communicates the rocking movements of lever 50 to the rack. By the arrangement of levers described the movements of the inertia member 38 are communicated to the sliding rack 34, the rack being moved longitudinally on the bed 12 when the member 38 moves, and in a direction opposite to the direction in which the member 38 moves. Because of the mechanical advantage of the system of levers employed the rack will be moved only a very short distance as compared with the distance through which the inertia member will move, but will be thrust longitudinally with great force against any object which it may engage. Thus, during deceleration of the bed on its printing stroke, when the teeth of rack 34 and gear segment 32 are in mesh, the following or rearwardly facing surface of each

successive tooth of the sliding rack 34 will be positively and strongly thrust against the forwardly facing surface of that tooth of segment 32 which immediately follows, during a brief instant of time, the tooth t of rack 34, for instance, being thrust against tooth t' of the gear segment when these teeth occupy the positions in which they are shown in Figure 5, one end of the line of contact being indicated at M. The force transmitted to gear segment 32 is communicated through the cylinder (which is represented in Figures 4 and 5 by shaft 22c) to main cylinder gear 30 and serves to maintain contact between each cylinder tooth and the following rack tooth at the point of mesh, for instance between the rear or following face of tooth t^3 and the leading face of the following rack tooth t^2 along a line of contact one end of which is indicated at N. The pressure of the sliding rack against the teeth of segment 32 is at all times sufficiently great to maintain firm contact between the meshing teeth of gear 30 and rack 28, despite any possible flywheel effect of the cylinder.

While the bed is accelerating upon its return stroke the inertia member 38 will continue to occupy the position in which it is shown in dotted lines in Figure 2 and hence the cylinder will be driven by the sliding rack 34 and close contact between meshing teeth of rack 28 and gear 30 maintained although, upon this return movement of the bed, it is not important that this action take place. As soon as deceleration on the non-printing stroke begins, however, the member 38 will move to its full line position and the sliding rack will assume the position in which it is shown in Figure 4 with relation to the bed, tooth pressure between the meshing teeth of rack and gear segment being relieved.

It will be appreciated that the design and arrangement of the component elements of the invention may be considerably modified without sacrifice of benefit. To avoid the application of torque to the cylinder, for instance, the sliding and stationary racks may be both positioned on the same side of the bed of the press. Furthermore, the mechanism disclosed, in somewhat different form, may be applied to the type of press in which the cylinder is rotated at a variable speed during the printing stroke. It may be advantageously employed in association with a press in which the cylinder makes one complete revolution at a variable linear speed conforming to that of the type bed and then remains at rest during the time when the type bed is returning to its initial position. The invention is also of utility when employed upon a two-revolution press in which the cylinder is rotated continuously in one direction but at a linear speed which conforms to that of the type bed during the printing stroke of the bed.

In the design of an inertia device for application to any certain press it will be kept in mind that, even when the press is to be operated at high speed, the frictional forces opposing slip between bed and cylinder are substantial and that it is only necessary to provide an inertia device of such capacity as to be capable of applying a force to the cylinder which, when added to the frictional force opposing slip, can successfully resist the momentum or flywheel action of the cylinder. Hence the size of the inertia mechanism to be applied to the bed may be minimized and the weight of the press kept as low as possible.

In calculating the force to be applied to the cylinder by the inertia mechanism it will also be

recognized that the force opposing cylinder fly-wheel action developed by an inertia mechanism of the type disclosed herein will be at all times proportional to the inertia force developed by the cylinder itself. An inertia mechanism fully capable of resisting the momentum of the cylinder, and making no allowance for the effect of frictional resistance to slip between bed and cylinder may readily be designed, based upon this fact, but for reasons set forth it is preferred to take advantage of the normal resistance to slip between bed and cylinder.

Having thus described the invention, what is claimed as new and desired to be secured by Letters Patent is:

1. In a printing press, in combination, a printing couple, means supporting each member of said couple, respectively, for oscillatory movement, means for driving one member of said couple with an accelerating-decelerating motion, and gearing connecting said members to cause movement of one when the other is driven, said gearing including means responsive to change in velocity of one of said members for maintaining constant tooth contact and preventing relative movement of said members during a printing operation.

2. In a printing press, in combination, a printing couple, means supporting the members of said couple for oscillatory movement, means for driving one member of said couple on its printing stroke with an accelerating-decelerating motion, and mechanism connecting said members to cause both to move when one is driven on its printing stroke, said mechanism including gearing and means responsive to change in velocity of one of said members for maintaining constant pressure of those teeth of said gearing which are associated with the driving member against the teeth associated with the driven member when said members are decelerating during a printing operation.

3. In a printing press, in combination, a printing couple, means supporting the members of said couple for oscillatory movement, means for driving one member of said couple on its printing stroke with an accelerating-decelerating motion, and mechanism connecting said members to cause both to move when one is driven on its printing stroke, said mechanism including a rack mounted upon one member, a gear mounted upon the other member, the teeth of rack and gear intermeshing during deceleration of said members while printing, and means responsive to change in velocity of one of said members for maintaining the teeth of rack and gear in constant driving engagement when said members are decelerating during a printing operation.

4. In a printing press, in combination, a printing couple, means supporting the members of said couple for oscillatory movement, means for driving one member of said couple on its printing stroke with an accelerating-decelerating motion, and mechanism connecting said members to cause both to move when one is driven on its printing stroke, said mechanism including gearing, an element mounted upon one member for movement forwardly with respect thereto, because of its inertia, when said member is decelerating on its printing stroke, and means connected to said element so as to be actuated thereby, for maintaining those teeth of the gear-

ing which are associated with the driven member in constant contact with those teeth which are associated with the driving member when said members are decelerating during a printing operation.

5. The combination set forth in claim 4 in which said second means comprises a plurality of levers for multiplying the force developed by said inertia propelled element.

6. In a press of the type described, a cylinder having a gear rigidly mounted thereon, a bed having fixed thereon a rack the teeth of which mesh with those of the gear, means for driving the bed on its printing stroke with an accelerating-decelerating motion, and mechanism associated with the bed and cylinder and responsive to change in velocity of the bed for maintaining the teeth of the cylinder gear in constant contact with the teeth of said rack when the bed is decelerating on its printing stroke.

7. In a press of the type described, a cylinder having a gear rigidly mounted thereon, a bed having fixed thereon a rack the teeth of which mesh with those of the gear, means for driving the bed on its printing stroke with an accelerating-decelerating motion, and mechanism including a second gear mounted upon the cylinder, a rack movably mounted on the bed, and inertia actuated means mounted upon the bed, for maintaining the teeth of said first gear and rack in constant engagement when the bed is decelerating upon its printing stroke.

8. In a press of the type described, a cylinder having a gear rigidly mounted thereon, a bed having fixed thereon a rack the teeth of which mesh with those of the gear, means for driving the bed on its printing stroke with an accelerating-decelerating motion, and mechanism for preventing relative movement of said bed and cylinder due to backlash between teeth of said rack and gear when the bed begins to decelerate while moving on its printing stroke, said mechanism including a second rack mounted on the bed in parallelism to said first rack for limited longitudinal sliding movement, an inertia element mounted on the bed for movement in a direction parallel to the direction of bed movement, means connecting said element and sliding rack whereby the rack is moved rearwardly of the bed when the bed is decelerating on its printing stroke, and a second gear fixed on said cylinder and in mesh with said sliding rack.

9. The combination set forth in claim 8 in which said last mentioned means includes two inter-connected levers pivotally mounted upon and extending transversely of the bed, whereby a reduced motion is communicated to the sliding rack.

10. The combination set forth in claim 8 in which the cylinder gears are mounted upon the cylinder at the opposite ends thereof and the racks are mounted, respectively, upon the sides of the bed.
